(57) **CLAIM**

The ornamental design for an Arduino matrix screen enclosure, as shown and described.

DESCRIPTION

FIG. 1 is a perspective view of the Arduino matrix screen enclosure;

FIG. 2 is a back view thereof;

FIG. 3 is a right side view thereof;

FIG. 4 is a left side view thereof;

FIG. 5 is a top side view thereof;

FIG. 6 is a bottom view thereof; and,

FIG. 7 is an exploded view thereof.
